UNITED STATES PATENT OFFICE

2,097,220

MECHANICAL SELF-STOPPING DEVICE FOR
PICTURES WITH AN AUTOMATIC RE-
STARTER

Raymond Blum, Paris, France

Application July 20, 1936, Serial No. 91,626
In France July 25, 1935

3 Claims. (CL 88—18.4)

This invention relates to a film feeding mechanism for a moving picture machine, characterized by the fact that the alternating movement of the claw-coupling, usually driven by a rigid part, is in this case operated by actuating means so constructed that it is possible to stop or suppress the inward movement of the claw-coupling into the film-holes without at the same time stopping movement of the various parts of the apparatus.

The mechanism is so constructed that should the claw-couplings be driven into the holes by a cam blocked for the purposes of the stoppage, the driving cam continues to operate the claws, owing to the adaptability of the mechanism to this movement.

If the claw-couplings are fixed to a swing-lever with a simultaneous forward and backward movement produced by a cam, the blocking of this cam for the purposes of the stoppage nevertheless permits of the swing-movement, owing to spring which acts upon the lever.

Devices constructed in accordance with this invention permit instant stoppage of the projection, as the only inertia to be surmounted is the very slight inward movement of the claw-couplings, which is held up while the other parts remain in movement. In the preferred embodiment of the invention the apparatus is composed exclusively of rotating parts to the exclusion of sliding parts which are liable to jam.

The invention is illustrated in the accompanying drawing, wherein:—

Fig. 1 is a front view showing a stopping device of the improved construction applied to a projection apparatus of the Oehmichen type, with claws mounted on a frame with an alternating drive.

Fig. 2 is a diagrammatical view of the mechanism shown in Fig. 1.

Fig. 3 is a vertical section with parts in elevation.

The claw coupling 1 which carries the points 2 is mounted on a frame 3 driven alternately upwards and downwards by a cam 4 which rotates around an axle or shaft 6. The points 2 also have horizontal movements, forwardly and rearwardly imparted to them by a cam 5 carried by the shaft 6, so that during their downward movement, the points which engage in marginal perforations of the film will carry the film with them, disconnection of the points from the film taking place during the upward movement. In order to stop movement of the picture, all that is necessary is to check the forward movement

of the points, but they can be permitted to continue their vertical reciprocating movement.

In order to permit continuous operation of the cam 5, a spring 7 is introduced between cam 5 and the upper portion 8 of the claw 1. Accordingly if the upper portion of the claw remains immovable, the cam 5 can continue to operate the spring 7 producing the necessary compensation.

On one of the branches or arms 8 of the claw 1 is fixed a blade 10 which extends downwardly and is of sufficient length to have its lower end engaged with an idler 11, which, when even with blade 10 prevents rotation of the claw-coupling around the axle 12. The film may thus be freed from the claw-coupling by bringing the idler 11 into position to engage the blade 10. For this purpose the idler 11 is provided with a flange 13 which serves as a check for blade 10, which is yieldably held in its normal position by an elastic retainer 14 but is permitted to revolve around axle 15.

For the purpose of this drive, the disc 14 has a triangular lever arm 16 upon which acts a cam 17 keyed as shown at 18 on to a shaft 19. Normally the lever 16 does not come into contact with cam 17, the shaft 19 being at rest and the disc 14 out of position towards the left of Fig. 2, so that the idler 11 is free and permits movement of the claw back and forth. On the shaft 19 is keyed cam 20 having a notch for receiving a latch 21 which is drawn in any desired manner. This latch projects and enters the notch of cam 20 which is fixed as is shaft 19. When the cam 20 and the shaft are liberated the spring 22 which is anchored to the side pin 23 of the cam 20, exerts pull upon the latter when freed from the latch 21, and the shaft 19 rotates and cam 17 acts upon lever 16 to swing the disk 14 about the pivot shaft or axle 15 and effect a sudden displacement of disk 14 to the left. As a consequence, the claw ceases its back and forth movement and the film is no longer engaged. Disconnection of cam 20 frees shaft 19, which through the main shaft 25 operates a blade 26 which, in its turn operates ratchet wheel 27 secured to the shaft by a pin 28. The shaft 19 can now rotate slowly, so as gradually to withdraw cam 17 from contact with the lever 16 and the disc 14 is withdrawn by elastic retainer 24 and the idler is again free.

During this time the cam 20 also will be turned and gradually taunt spring 22, and as soon as cam 20 has a sufficient distance to bring its notch into position opposite the latch, the latch

will move into the notch and hold the cam stationary, until the latch is again shifted away from the cam.

Needless to state, the examples of application shown in the drawing are only those of non-limitative character, the invention permitting of variants and modifications according to the type and model of the apparatus upon which the devices are mounted.

10 I therefore claim:

1. In a motion picture projecting machine, a film feeding mechanism including a vertically reciprocating frame, a film-feeding clutch extending vertically in front of said frame and having its lower end pivoted to the frame and its upper portion projecting above the frame and provided with film engaging claws extending away from the frame, a spring arm extending from the upper end of said clutch over the upper end of the frame, a rotary shaft, a cam carried by said shaft and operating in the frame for reciprocating the frame, a second cam carried by said shaft and engaging the spring arm for rocking the clutch towards and away from a film during vertical reciprocation of the frame and clutch, a blade carried by said clutch and extending downwardly therefrom below said frame, an abutment member movable into and out of position to engage the lower portion of said blade and control tilting of the clutch, and, means for adjusting the abutment member.

2. In a motion picture projecting machine, film

feeding mechanism including a vertically reciprocating frame, a film-feeding clutch extending vertically in front of said frame and having its lower end pivoted to the frame to mount the clutch for swinging movement relative to the frame into and out of feeding engagement with a film, a spring arm extending from the upper end of said clutch over said frame, means for reciprocating the frame and acting upon said arm to effect swinging of the clutch during reciprocation of the frame, a blade carried by said clutch at one side thereof and extending vertically below the clutch and downwardly beyond the lower end of the frame, and control means including a member movable into and out of position to engage the lower end portion of said blade and prevent tilting of the clutch into position to have feeding engagement with a film.

3. The structure as claim 2 wherein the control means consists of a driven shaft rotatably mounted transversely of the blade in crossing relation to the lower portion thereof, a disc pivotally mounted for swinging movement about a vertical axis into and out of position to engage the blade and prevent movement of the clutch towards a film, a lever arm extending laterally from said disc at the vertical axis thereof, a cam carried by said driven shaft for engaging said lever arm and swinging the disc about its axis, and means for controlling rotation of the driven shaft.

RAYMOND BLUM.
